UNITED STATES PATENT OFFICE.

ORLANDO C. BLACKMER, OF OAK PARK, ILLINOIS.

COPY-HOLDER.

SPECIFICATION forming part of Letters Patent No. 424,086, dated March 25, 1890.

Application filed October 24, 1889. Serial No. 328,064. (No model.)

To all whom it may concern:

Be it known that I, ORLANDO C. BLACKMER, a citizen of the United States, residing at Oak Park, in the county of Cook and State of Illinois, have invented certain new and useful 5 Improvements in Copy-Holders, of which the following is a specification.

My invention relates to certain improvements in means for holding the copy or note book of reporters, stenographers, and others, sketch-books of artists, or the tablets of accountants, both while the writing or sketching is being done and also while the writing or sketching is being copied.

15 In carrying out my invention I provide a rigid base of wood, heavy card-board, or similar material which will furnish a suitable rigid support for the paper, note-book, or other material on which the writing or sketching is done, and to support said material on the base I employ a light wire or bar having formed at its ends integral coils which are adapted to embrace the opposite sides of the base, the coils being compressed when applied. The book, paper, or other material being then inserted beneath the wire or bar, the spring-coils will tend to hold the same tightly clamped upon the base, and the leaves may be turned over in succession as fast as 20 filled. The base, with the writing or sketching material secured thereon, will be sufficiently stiff to provide a suitable writing or sketching surface to prevent the doubling or folding of the leaves, and yet not so heavy but that it may be held conveniently in one hand while the writing or sketching is being done with the other. In order to support the base with the copy secured thereon in position to have the matter copied, I apply to the back 25 of the said base a support, preferably in the form of a strip or wire of resilient material, having two parallel legs and a central portion bent upwardly and adapted to engage at its upper end a suitable stop formed in or on the back of the base. This support will sustain the base with the copy at the proper angle for convenient reading, and may be folded flat against the back of the base when not in use.

30 In the accompanying drawings, Figure 1 is a front elevation of the copy-holder, the writing being in this case the common stenog-

rapher's note-book, the rod in this instance being clasped between the leaves of the book. Fig. 2 is a similar view showing the note-book, which opens sidewise. Fig. 3 is a rear elevation showing the support and a modified form of securing the clamping-wire to the base; and Fig. 4 is a side elevation showing the copy-holder supported in position for 55 copying therefrom, the leaves of the note-book being thrown back.

A represents the base in convenient form and made from some light but stiff material, such as veneer or other light stiff material.

55 B is a clamping-wire having a straight body portion equal to the width of or length of the base, according as it is desired to support the material at the top or along the side of said base. This clamping-wire has integrally 60 formed at its ends the coils b, which are conveniently made by giving the ends two or more coils about the body portion, and preferably so that the ends of the body portion are extended through the said coils. In order 65 to secure the ends of these coils to the base, the last coil may be formed at right angles to the others; or the wire may be simply straightened and bent parallel to the body-wire, or at such distance from the body-wire as to permit 70 the edges of the base to be embraced between them. The clamping-wire is put on with the coils only slightly compressed, and the further compression of the coils by the 75 passage of the paper beneath the clamping-wire 75 serves to draw the latter tightly down upon the material, thus holding it firmly and securely to the base.

80 The support comprises parallel legs C C, whose upper ends are secured to the edge of 85 the base, and the upwardly-bent arms c c, which may be converged to a point midway between the arms C C and of about half their length.

85 D is a stop, in this instance formed simply by notching or cutting the back of the base, which adapts it to receive the ends of the arms 90 c c. These parts are all made integrally from a single piece of wire or of sheet metal or like flexible resilient material, and in use the 95 parts c c are flexed until their upper ends enter the notch d, as shown in Fig. 4, in which 100 position the base will be supported in an inclined position for the use of copyists.

The support itself may be adapted to a variety of uses other than the holding of copy, and I do not therefore desire to claim the same except in combination with the other 5 elements of a copy-holder. The support is claimed in an application filed of even date herewith.

I provide means for preventing the leaves which have been written or sketched upon 10 and thrown back closing again, and said means comprise a rigid bar or wire E, having bent ends e secured to the base in any convenient manner. As shown, the bent ends e enter apertures in the upper edge of 15 the base, and the leaves, being thrust under the body portion, are prevented from folding back, as they would otherwise, owing to the tendency of the binding to close the leaves together or accidental causes. I have also 20 provided a marking-finger F, which is constructed from a single piece of wire doubled upon itself, so that the free ends are brought together, and the looped end is preferably bent and spread to provide the clamping-jaws 25 f and f', which are adapted to engage the edge of the base, along which it may be slipped to indicate the progress of the copying.

I claim—

1. A copy-holder comprising, in combination, a suitable stiff base and a clamping-wire 30 of a length to extend across the face of the base, and having integral coils at each end

thereof whose turns encircle the wire, the extreme ends of the wire being bent at an angle to the coils, whereby to adapt them to 35 embrace the edges of the base, substantially as described.

2. A copy-holder comprising, in combination, a suitable stiff base, a clamping-wire having integral coils at each end thereof and 40 a straight portion adapted to embrace the edges of the base, and a support for said base, comprising supporting-legs and bracing-arms, substantially as described.

3. A copy-holder comprising, in combination, a suitable stiff base, a clamping-wire having integral coils at each end thereof and straight portions to embrace the edges of the base, and a bent wire having its ends inserted in the edge of the base at its top, and adapted 50 to permit the passage of the leaves between it and the edge of the base to prevent their folding, substantially as described.

4. A copy-holder comprising, in combination, a suitable stiff base and a clamping-wire to secure the copy thereon, and a detachable marking-finger constructed from a resilient material, having an integral clamp at one end thereof to embrace the edge of the base, substantially as described.

ORLANDO C. BLACKMER.
